Inventor:
William A. Moran,
By his Attorneys
Fraentzel and Richards,

UNITED STATES PATENT OFFICE.

WILLIAM A. MORAN, OF NEWARK, NEW JERSEY.

CROWD-RESISTING APRON OR GUARD FOR MOTOR-VEHICLES.

1,856,874.

Specification of Letters Patent. Patented Oct. 26, 1920.

Application filed August 15, 1919. Serial No. 317,695.

To all whom it may concern:

Be it known that I, WILLIAM A. MORAN, a citizen of the United States, residing at Newark, in the county of Essex and State of New Jersey, have invented certain new and useful Improvements in Crowd-Resisting Aprons or Guards for Motor-Vehicles; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in motor-vehicles; and, the present invention relates, more particularly, to an improved attachment to a motor-cycle, in the form of a protector-guard, apron, skirt, or the like, which is easily and quickly attachable to a motor-cycle, or similar vehicle, to adapt the same for use, during parades or large gatherings of people upon the streets, in pressing back, into line upon the curb or other designated place in the street, the surging crowd without danger of injury to the persons in the crowd.

The present invention, therefore, has for its principal object to provide a novel and simply-constructed attachment for use with motor-cycles and similar vehicles, whereby the same are especially adapted for use for traffic officers, in pressing back forwardly surging crowds, in precisely the same manner as is now done by horse-mounted police, the attachment being made in the form of a guard or apron, mounted upon one side of the frame of the vehicle, and extending around the front and rear of the vehicle, the apron being of such arrangement and shape, that it will push back the crowd, without injury to the persons with whom the apron of the moving vehicle is brought in contact.

Other objects of the present invention not at this time more particularly enumerated will be clearly understood from the following detailed description of the present invention.

With the various objects of the present invention in view, the said invention consists, primarily, in the novel guard or apron-attachment for motor-vehicles hereinafter more fully set forth; and, the present invention consists, furthermore, in the novel arrangements and combinations of the several

devices and parts, as well as in the details of the construction of the said parts, all of which will be more fully described in the following specification, and then finally embodied in the clauses of the claims which are appended to and which form an essential part of the said specification. 60

The invention is illustrated in the accompanying drawings, in which:— 65

Figure 1 is a side elevation of a motor-cycle and a safety-guard or apron attached thereto, showing one embodiment of the principles of the present invention; Fig. 2 is a top or plan view of the devices represented in said Fig. 1; and Fig. 3 is a rear end view of the same. 70

Fig. 4 is a detail view of a portion of the safety-attachment, skirt, or apron, showing a portion of the said attachment provided with a reinforcing or strengthening means. 75

Similar characters of reference are employed in all of the said above described views, to indicate corresponding parts.

Referring now to the said figures of the drawings, the reference-character 1 indicates any usual frame-work of a motor-cycle, comprising the steering-fork 2, and the truss-members 3. 80

Suitably connected with and extending laterally from the said truss-members 3 are supporting members or elements, usually in the form of rods, as 4, any number of such rods being used, and said rods having their outer ends suitably secured to receiving 85 sockets 5, or other suitable fastening means, suitably secured upon the inner surface-portions of a guard, apron, or skirt, as 6. This guard or apron is usually of the general configuration shown in the drawings, the lower 90 portion of the same being inwardly curved, as at 7, so as to provide a suitably flanged portion along the lower marginal edge of the guard or apron, substantially as shown in Fig. 2 of the drawings. At its respective 95 ends, the said guard or apron is formed with curved portions 8 and 9, terminating in angularly extending guarding members, as 10 and 11, these members partially incasing the wheels of the motor-cycle, and providing 100

suitable safety-guards or fenders to prevent injury to a person when driving the vehicle into or against a mass or crowd of people. From an inspection of Figs. 1 and 3 it will be seen that the said guard or apron is 110 of such height from the ground, both at the top and bottom, that the actions of the op-

erator or driver of the vehicle will not be interfered with; and, furthermore, that no obstructions to the running of the vehicle will be presented, and that the vehicle can 5 readily be driven upon the curb at the sidewalk of a street, or onto a safety isle should this be necessary.

To strengthen the guard or apron, which is made of sheet metal, the same may be reinforced and strengthened by securing upon 10 its inner face, in any desirable location, a bracing means, such as is shown in Fig. 4 of the drawings, the same consisting of a series of longitudinally extending frame- 15 members 12, cross-members 13, and struts or braces 14, all preferably made of wood, or other suitable light material. Extending from the frame-work of the vehicle, preferably at the rear end-portion of said frame, 20 is a suitably constructed and laterally extending auxiliary frame-connection, as 15, carrying an auxiliary wheel 16, the purpose of which is to properly balance the vehicle, as will be clearly evident.

25 In using the guard, apron, or skirt, in traffic upon a motor-cycle, it is customary to use the attachment upon the right-hand side of the vehicle, the latter being propelled by the officer against the front line of the 30 surging crowd, the guard or apron striking said line slantingly without harm to the people; it will be understood, however, that such guard or apron may be used upon the left-hand side of the vehicle, or such guards 35 or aprons may be used upon both sides of the vehicle, if desired.

It will be understood, therefore, that I do not limit my present invention to the exact arrangements and combinations of the 40 several devices and parts, nor to the details of the construction of the said parts, as set forth in the foregoing specification, and as defined in the clauses of the claims which are appended to the said specification. 45 Hence, I do not limit my present invention to the exact arrangement and combinations of the several devices and parts as described in the said specification, nor do I confine myself to the exact details of the construction, 50 nor to the shape or configuration of the said guard or apron, as shown in the accompanying drawings.

I claim:—

1. In combination with the frame of a 55 motor-vehicle, a crowd-resisting safety-guard or apron, said apron having its end- portions embracing the wheels of the vehicle, and a means of attachment for securing the same in position upon said frame.
- 60 2. In combination with the frame of a motor-vehicle, a crowd-resisting safety-guard or apron, said apron having its end- portions embracing the wheels of the vehicle, and a means of attachment for securing 65 the same in position upon one side of

said frame, said guard or apron being provided at the front and rear with inclosing portions.

3. In combination with the frame of a motor-vehicle, a crowd-resisting safety- 70 guard or apron, said apron having its end- portions embracing the wheels of the vehicle, and a means of attachment for securing the same in position upon said frame, said guard or apron being provided along its 75 lower marginal edge-portion with an inwardly extending flange.

4. In combination with the frame of a motor-vehicle, a crowd-resisting safety- 80 guard or apron, said apron having its end- portions embracing the wheels of the vehicle, and a means of attachment for securing the same in position upon said frame, said guard or apron being provided along its 85 lower marginal edge-portion with an inwardly extending flange, and said guard or apron being provided at the front and rear with inclosing portions.

5. In combination with the frame of a motor-vehicle, a crowd-resisting safety- 90 guard or apron, said apron having its end- portions embracing the wheels of the vehicle, and a means of attachment for securing the same in position upon said frame, and a reinforcing truss-frame mounted against the 95 inner surface-portion of said guard or apron.

6. In combination with the frame of a motor-vehicle, a crowd-resisting safety- 100 guard or apron, said apron having its end- portions embracing the wheels of the vehicle, and a means of attachment for securing the same in position upon said frame, and a reinforcing truss-frame mounted against the 105 inner surface-portion of said guard or apron.

7. In combination with the frame of a motor-vehicle, a crowd-resisting safety- 110 guard or apron, said apron having its end- portions embracing the wheels of the vehicle, 115 and a means of attachment for securing the same in position upon said frame, said guard or apron being provided along its lower marginal edge-portion with an inwardly extending flange, and a reinforcing truss- 120 frame mounted against the inner surface- portion of said guard or apron.

8. In combination with the frame of a motor-vehicle, a crowd-resisting safety- 125 guard or apron, said apron having its end- portions embracing the wheels of the vehicle, and a means of attachment for securing the same in position upon said frame, said guard or apron being provided along its lower marginal edge-portion with an inwardly extending flange, and said guard or apron being provided at the front and rear with inclosing portions, and a reinforcing truss- 130 frame mounted against the inner surface- portion of said guard or apron.

9. In combination with the frame of a motor-vehicle, a crowd-resisting safety-guard or apron, said apron having its end-portions embracing the wheels of the vehicle, 5 and tie-rods extending from the vehicle-frame and connected with said guard or apron for securing the same in position.
10. In combination with the frame of a motor-vehicle, a crowd-resisting safety-guard or apron, said apron having its end-portions embracing the wheels of the vehicle, and tie-rods extending from the vehicle-frame and connected with said guard or apron for securing the same in position upon 15 one side of said frame, said guard or apron being provided at the front and rear with inclosing portions.
11. In combination with the frame of a motor-cycle, a crowd-resisting safety-guard or apron, said apron having its end-portions embracing the wheels of the vehicle, and tie-rods extending from the vehicle-frame and connected with said guard or apron for 20
- securing the same in position, said guard or apron being provided at its lower marginal 25 edge-portion with an inwardly extending flange.
12. In combination with the frame of a motor-cycle, a crowd-resisting safety-guard or apron, said apron having its end-portions 30 embracing the wheels of the vehicle, and tie-rods extending from the vehicle-frame and connected with said guard or apron for securing the same in position, said guard or apron being provided at its lower marginal 35 edge-portion with an inwardly extending flange, and said guard or apron being further provided at the front and rear with inclosing portions.

In testimony that I claim the invention 40 set forth above I have hereunto set my hand this 13 day of August, 1919.

WILLIAM A. MORAN.
